CLAIM

The ornamental design for a support for supporting plants for aeroponic treatment, as shown and described.

DESCRIPTION

FIG. 1 is a perspective view of a support for supporting plants for aeroponic treatment showing my design;
FIG. 2 is a top plan view thereof;
FIG. 3 is a front elevation view thereof, the back elevation view being a mirror image;
FIG. 4 is a bottom plan view thereof; and,
FIG. 5 is a right side elevation view thereof, the left side elevation view being a mirror image.
